(57) **CLAIM**

The ornamental design for a multi grip star bit, as shown and described.

DESCRIPTION

FIG. 1 is a perspective view of a multi grip star bit showing our new design;

FIG. 2 is a front elevational view thereof;

FIG. 3 is a right-side elevational view thereof;

FIG. 4 is a rear elevational view thereof;

FIG. 5 is a left-side elevational view thereof;

FIG. 6 is a top plan view thereof;

FIG. 7 is a bottom plan view thereof;

FIG. 8 is a lateral view thereof;

FIG. 9 is a lateral view thereof, rotated 45 degrees from the position in FIG. 8;

FIG. 10 is a lateral view thereof, rotated 45 degrees from the position in FIG. 9;

FIG. 11 is a lateral view thereof, rotated 45 degrees from the position in FIG. 10; and,

FIG. 12 is a lateral view thereof, rotated 45 degrees from the position in FIG. 11.
